DESIGN FOR A STEERING POST SHROUD FOR A BICYCLE

John R. Morgan, Oak Park, Ill., assignor to Sears,
Roebuck and Co., Chicago, Ill., a corporation of
New York

Application August 28, 1939, Serial No. 86,919

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Steering Post Shroud for a Bicycle, of which the following is a specification, reference being had to the accompanying drawing, forming a part thereof.

Fig. 1 is a front elevation of a steering post

shroud for a bicycle, embodying my new design.

Fig. 2 is a side elevation of the same, the opposite side being of the same appearance as the side shown.

Fig. 3 is a top plan view of the same.

I claim:

The ornamental design for a steering post shroud for a bicycle, substantially as shown and described.

JOHN R. MORGAN.
